UNITED STATES PATENT OFFICE.

EDWIN S. RAUWORTH, OF DE KALB, ILLINOIS, ASSIGNOR TO APOLLO PIANO COMPANY, OF DE KALB, ILLINOIS, A CORPORATION OF ILLINOIS.

PIANO-ACTION BRACKET.

Application filed December 4, 1922. Serial No. 604,668.

To all whom it may concern:

- Be it known that I, EDWIN S. RAUWORTH, a citizen of the United States, residing at De Kalb, in the county of De Kalb and State of Illinois, have invented certain new and useful Improvements in Piano-Action Brackets, of which the following is a specification, reference being had to the accompanying drawings, forming a part thereof.
- 10 The purpose of this invention is to provide an improved bracket for use in grand piano actions, primarily, to replace the more usual wooden brackets by which the action rails are supported upon the key-bed. It
- 15 consists of certain features of construction as hereinafter described and shown in the drawings and as indicated by the claims.
- In the drawings:—
- Figure 1 is a vertical sectional view of a part of a grand piano showing a bracket embodying this invention mounted in position of use.
- Figure 2 is a top plan view of the bracket itself.
- 20 Figure 3 is a side elevation of the bracket.
- Figure 4 is a detail section taken as indicated at line, 4—4, on Figure 3.
- The bracket embodying this invention is preferably made of sheet metal of moderate
- 25 thickness. Each bracket is composed of two blanks, 1 and 2, secured together face to face, and I have found that if ordinary rolled steel stock of about one-sixteenth-inch in thickness is used for these blanks, the resulting bracket is amply stiff, while at the same time it is so much thinner than the common wooden brackets now in use as to nearly eliminate the so-called "breaks" in the action. Each blank is formed with two
- 30 foot portions at opposite ends of its bottom edge, and these portions are offset to provide channels, 3 and 4, extending at right angles to the bottom edges so that when the two blanks are assembled, each foot portion has a vertically extending bore to receive securing screws, *a* and *b*, by which it is mounted in position on the supporting block, *h*, which in turn rests on the key frame, *j*, of the piano.
- 35 The blanks, 1 and 2, are formed with substantially the same outlines as the wooden brackets in common use so as to provide lodgment for the rails, *f*, and *g*, which constitute supports for the hammers and other

parts of the action. Adjacent the upper edges of the bracket upon which these rails are lodged, the blanks, 1 and 2, are formed with elongated offset depressions, 5 and 6, registering opposite each other when the blanks are assembled to provide sockets which are preferably screw threaded to receive the attaching screws, *c* and *d*, for the rails, *f* and *g*, respectively.

For securely fastening together the blanks, 1 and 2, I form two apertures in the blank, 1, and force the material of the blank, 2, through these apertures as indicated at 7 in Figure 4, somewhat in the manner of hollow rivets, clinching the material over the outer face of the blank, 1. Then in addition, I spot-weld the two blanks together at numerous points, as indicated at *w*, so that in effect I have a substantially flat bracket about one-eighth of an inch in thickness standing on edge on the mounting block, *h*, the offset portions, 3 and 4, somewhat widening the footing of the bracket upon said block. At the upper ends of the bores formed by the offset channels, 3 and 4, the blanks are cut with edges parallel to the bottom edge so that the heads of the screws, *a* and *b*, may be turned down tightly to clamp the bracket in position on the block, *h*. The result is a bracket quite economical to manufacture and very satisfactory in service.

I claim:—

1. A piano action bracket composed of two similar sheet metal blanks assembled face to face, one blank being formed with an aperture and the material of the other blank opposite said aperture being forced through the aperture and clinched over against the apertured blank in the manner of a hollow rivet for holding said blanks together.

2. A piano action bracket composed of two similar sheet metal blanks secured together face to face and formed with opposing elongated depressions which constitute sockets opening through the edge of the blank, said sockets being threaded to receive securing screws.

In testimony whereof, I have hereunto set my hand at Chicago, Illinois, this 28th day of November, 1922.

EDWIN S. RAUWORTH.
